UNITED STATES PATENT OFFICE.

THOMAS GUNNING, OF PITTSBURG, PENNSYLVANIA.

SMOKE-CONSUMER.

SPECIFICATION forming part of Letters Patent No. 514,457, dated February 13, 1894.

Application filed March 6, 1893. Serial No. 464,647. (No model.)

To all whom it may concern:

Be it known that I, THOMAS GUNNING, of Pittsburg, in the county of Allegheny and State of Pennsylvania, have invented a new and useful Improvement in Smoke-Consumers, of which the following is a full, clear, and exact description, reference being had to the accompanying drawings, in which—

Figure 1 is a horizontal sectional view through the combustion-chamber of a battery of boilers, on the line I—I of Fig. 2, provided with my improved smoke consumer. Fig. 2 is a vertical sectional view, on the line II—II of Fig. 1; and Figs. 3 and 4 are detail views, hereinafter referred to.

My invention relates to that class of smoke consumers wherein air is forced in over the grates to combine with and consume the smoke, and it consists in an improved construction, whereby air entering at the sides is heated by exposed side-pipes and forced in at the front of the furnace.

In the drawings, in which similar numerals indicate like parts, 2 represents the front wall of the setting, through which pass the air-inlet pipes 3, there being one pipe for each boiler located over the furnace-door. These pipes are screwed into the casing, and to their projecting outer ends are joined the globular reservoirs or collectors 4, which are connected with each other by pipes 5. Leading from the end collectors are the bent pipes 6, which are embedded in the inner sides of the furnace walls, as shown, and are partially exposed to the heat of the furnaces. These pipes pass through apertures in the side-walls of the setting and are provided with the muffling-device 7, shown in Fig. 4. This device consists simply of a box or receptacle secured to the end of the pipe and having a slot in its side so that the entering air makes an angular turn before entering the pipe. I have found that this device is fully as effective as the complicated diaphragm mufflers now employed, while it is much simpler and cheaper. Through the outer portions of the reservoirs 4 pass the injector-pipes 8, which are joined by T-connections to the steam-pipe 9 passing in front of the boilers.

To increase the supply of air through the pipes 6, I may use steam-injector pipes 10

passing through the outer ends of the mufflers, and to bring a further supply of heated air to the central boilers, where there are several boilers in the battery, I employ the vertical pipes 1', having T-connections with the connecting pipes 5. These pipes 1' lead up into the breeching of the boiler, and at their upper ends are connected to the inlet pipes 12 passing through the uptake and having at their outer ends suitable rotatory dampers to regulate the amount of entering air.

The action of the device is as follows:—The air entering through the mufflers at the ends of the pipes 6, is heated by the action of the flame upon the exposed portions of the pipes, and thence passing to the reservoirs is forced in over the fire, and the heated air uniting with the smoke, consumes the same. Additional air is drawn down through the vertical supply pipes if necessary, being heated in transit by the waste products of combustion, and supplied to the reservoirs. The mufflers do away with the most of the noise occasioned by the entering air, and the amount of air may be increased by turning steam into the injectors 10 passing into said mufflers.

I claim as my invention—

1. A boiler furnace having a pipe partially embedded in its side wall and having an open end projecting therethrough, an air pipe leading through its front casing above the grate, an injector in the air pipe, and a connection between said pipe and the pipe in the side wall; substantially as described.

2. A boiler having a front reservoir provided with an air pipe projecting through its front casing, a vertical pipe extending therefrom up through the breeching, and provided with an extension projecting through the side of the uptake and opening into the atmosphere; substantially as described.

3. A boiler having an air pipe partially embedded in its side wall, said pipe opening outwardly through the side wall and being connected to a reservoir in front of the furnace, and an air pipe leading from said reservoir into the space above the grate; substantially as described.

4. A boiler having an air pipe partially embedded in its side wall, said pipe opening outwardly through the side wall and being con-

nected to a reservoir in front of the furnace, an air pipe leading from said reservoir into the space above the grate, and an injector passing into the front air pipe; substantially 5 as described.

5. A battery of boilers having air pipes partially embedded in the side walls, air pipes leading through the front casing and connected to the side pipes, vertical pipes also 10 connected to the front air pipes, leading up

through the breeching and passing through the side of the uptake, and injectors entering the front air pipes; substantially as described.

In testimony whereof I have hereunto set my hand.

THOMAS GUNNING.
